UNITED STATES PATENT OFFICE.

HIRAM N. WICKES, OF GRAND GORGE, ASSIGNOR TO ZOPHER W. MORE, OF CAMDEN, NEW YORK.

CAR-COUPING.

SPECIFICATION forming part of Letters Patent No. 224,754, dated February 17, 1880.

Application filed December 3, 1877.

To all whom it may concern:

Be it known that I, HIRAM N. WICKES, of Grand Gorge, in the county of Delaware and State of New York, have invented a new and Improved Car-Coupling, of which the following is a specification.

In the accompanying drawings, Figure 1 represents a vertical longitudinal section of my improved car-coupling, and Fig. 2 is a top view of the same with one head in horizontal section on line *x* *x*, Fig. 1.

Similar letters of reference indicate corresponding parts.

This invention has reference to an improved car-coupling that couples in reliable and automatic manner without requiring any one to step in between the cars, the link being held in horizontal position, so as to secure its entrance into the opposite draw-head; and the invention consists of a draw-head with internal cavity having upwardly-inclined rear portion and central guide-rib, along which a centrally-grooved roller is carried by the link.

The roller sustains the coupling-pin, the latter dropping into the link when the roller is carried back. The roller bears on the rear part of the link and holds it, in connection with the pin, in horizontal position for coupling.

Referring to the drawings, A represents a draw-head of the usual shape, with a curved and tapering mouth and internal cavity B. The rear part of the cavity B is extended back of the coupling-pin C in upwardly-inclined manner, and provided with a central rib, *a*, at the inclined rear wall of the enlarged cavity.

The center rib, *a*, serves to guide a cylindrical roller, D, that fits, by an annular center groove, *b*, on the guide-rib *a*. The central groove of the roller is, however, of less width than the diameter of the pin C, so that the roller may sustain the same in raised position. The roller C moves forward when the pin is

raised, and is retained by the contracted front portion of the cavity in such a position below 45 the upper pin-hole as to support the pin B in raised position, as indicated in Fig. 1.

In coupling, the entering link E strikes the roller, carries the same back into the rear cavity, and drops the pin for coupling the link. 50 The link strikes against the center rib, *a*, and is thereby prevented from entering farther into the draw-head and from injuring the roller by the concussion.

When it is desired to couple the draw-heads 55 the link is held in horizontal position by the pin and by the roller bearing on the rear end of the link, as shown in Fig. 1; so as to secure thereby the reliable entrance of the link into the approaching draw-head, even in case the 60 draw-heads to be coupled are of different heights.

The essential features of the coupling are 65 the grooved roller and the inclined guide-rib of the rear cavity of the draw-head.

I am aware that it is not new to use a roll in an automatic coupling; but the pin has been found, especially after its hole in the draw-head had become worn, to take a slightly oblique or laterally-inclined position on roll, 70 so as to drop on the side of link, and thus allow the cars to uncouple as soon as they started.

By my mode of receiving and guiding the pin in a median groove of roll it is carried down directly into the open space of link. Hence 75

What I claim as new is—

In an automatic car-coupler, the combination of the peripherally-grooved roller with the inclined rib, the coupling-pin, and recessed draw-head, substantially as described, to operate as specified. 80

HIRAM N. WICKES.
